(57) **CLAIM**

The ornamental design for an information terminal cradle, as shown and described.

DESCRIPTION

FIG. 1 is a perspective view of said information terminal cradle;

FIG. 2 is a bottom perspective view of said information terminal cradle;

FIG. 3 is a front view of said information terminal cradle;

FIG. 4 is a rear view of said information terminal cradle;

FIG. 5 is a left side view of said information terminal cradle;

FIG. 6 is a right side view of said information terminal cradle;

FIG. 7 is a top plan view of said information terminal cradle;

FIG. 8 is a bottom plan view of said information terminal cradle;

FIG. 9 is a perspective view upon opening lid of said information terminal cradle;

FIG. 10 is a perspective view with a terminal on said information terminal cradle; and,

FIG. 11 is a perspective view on the wall of said information terminal cradle.

The information terminal in FIG. 10 and wall in FIG. 11 shown in broken lines are included for environmental purposes only and are not part of the claim.
